UNITED STATES PATENT OFFICE.

LUIGI BRUNO, OF TURIN, ITALY.

AUTOMATIC CIRCULAR LOOM.

Application filed May 14, 1923. Serial No. 638,896.

To all whom it may concern:

Be it known that I, LUIGI BRUNO, a subject of the King of Italy, residing at Turin, in the Kingdom of Italy, have invented 5 certain new and useful Improvements in Automatic Circular Looms; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to automatic circular looms for the manufacture of all classes of fabrics in which the weft threads are wound upon flat bobbins and from the inside of which the thread unwinds. These 20 are contained in shuttles arranged radially in two planes and so controlled as to allow of very rapid weaving even when threads of different colours are used.

25 Another feature of this invention is a guide for the weft threads which allows them to be led radially almost up to the weaving point.

30 Another improvement is an electro-magnetic device for automatically stopping the machine if a thread breaks. The movements of the shuttles are also electro-magnetically controlled in place of the usual mechanical means.

35 The loom which forms the subject of the present invention has numerous advantages as it may be used for the weaving of plain and fancy fabrics and of both thread and metal materials since very thin wires may be used owing to the negligible strains to 40 which they are subjected.

The loom may be employed for the manufacture of sacks which owing to the tubular shape of the fabric would only have to be sewn at the end, and also for the manufacture 45 of hose and other pipes.

In the accompanying drawings Figure 1 is a diagrammatic partial section showing one method of carrying out the invention;

Figure 2 is a plan view.

50 Figures 3 and 4 show on a larger scale the mechanism for controlling the shuttles in the loom shown in Figures 1 and 2.

Figure 5 shows a shuttle box in perspective.

Figure 6 shows the hank contained in the 55 shuttle.

Figure 7 is a perspective view of the safety device for automatically stopping the machine when the warp thread breaks.

Figure 8 is a plan view of the flanged 60 joint between the drive and the arrangement for advancing the fabric.

Figure 9 is a section showing the outlet of the electric wires from the fixed pivot.

Figure 10 shows diagrammatically in section a second method of construction of the 65 loom.

Figure 11 is a plan view of Figure 10.

Figure 12 is a section showing the arrangement for controlling the shuttles. 70

Figure 13 is a plan of the arrangement shown in Figure 12.

Figure 14 shows the mechanism for retaining the shuttles.

Figure 15 is a section of the batten.

Figure 16 shows a modification of this arrangement.

Figure 17 is a side view of the comb.

Figure 18 shows an electro-magnetic arrangement for retaining the shuttles. 80

Figs. 19 and 20 show on an enlarged scale the operating means of the warp carriers.

Referring to Fig. 1, 1 is a hollow vertical journal supported at the top and provided with a platform 2 upon which is mounted an annular box 3 containing a series of mechanisms 4 which move the shuttles 5 from their position and place them in similar mechanisms 6 arranged in a corresponding annular box 7 supported by adjustable uprights 8.

Upon the journal 1 is mounted a member 9 free to rotate upon it and provided with an arm 11 carrying thread guides 12 fed 95 from the bobbins 10.

The rotating member 9 by means of the gear wheels 14, 14', 14'', 14''' drives a vertical shaft 15 whose lower end is screw-threaded causing the lowering of a circular feeder 16. The fabric is drawn off from the fabric supporting tube by the feeder 16 for a certain distance after which it is released and carried away upon the usual system of rollers.

At the start the movement of the feeder may be effected by hand.

The supporting arms 11 are provided

with teeth 13 acting upon the rollers 32 of the mechanisms 4, 6, and causing the exchange of the shuttles between the boxes 3, 7, directly after the passage of the support 11 on the rotating member 9.

The shuttles may be arranged in one or more series. Figure 2 shows them in two series. Each mechanism actuating the shuttles has a drive and return roller actuated at different times by the teeth 13.

The teeth 13 are removable from the arms 11 and may be placed therein in any one of a number of vertical arranged positions corresponding to the particular series of 15 shuttles to be operated to cross the weft thread. All the shuttles may cross the weft, but only certain selected shuttles may do so at given intervals.

By adjusting the position of the teeth 13 upon the supports 11 the successive movements of the shuttles may be altered and fancy fabrics and various colours of fabrics obtained.

Figures 3 and 4 show in detail the mechanism for controlling the shuttles. Such mechanism consists of lazy tongs, that is a system of parallelograms 21 guided by a support 22 to which the first parallelogram is pivoted at 23. The second is pivoted at 24 upon a movable support 25 provided with a rod 26 projecting through the box 7 and ending in a fork 27 upon which is mounted the shuttle 5 retained in position by the spring teeth 28 fixed to the annular box 7 and engaging with lugs 5'.

The parallelogram system 21 is operated by means of a sliding frame 29 connected to it by rods 30 and actuated by a beam 31 whose opposite end (Figure 4) carries 40 a main roller 32 and a return roller 33 mounted upon the arm 34 pivoted to the beam 31 and guided by a surface 35.

The apparatus works as follows:

As above mentioned the support 11 carries 45 besides the thread guide 12 a tooth 13 mounted upon the prolongation 11' at such a height that it is in the plane of the rollers 32, 32', 32'', 32''' corresponding to the four tiers of the shuttles. In the example shown 50 the four tiers are divided into three series, the mid series having double the number of shuttles of those contained in the other two series.

When the tooth 13 encounters a roller it 55 lowers it so causing the opposite end of the beam 31 to be raised and thus actuating the parallelogram system which raises the fork 27 with the shuttle 5 (against the action of the spring teeth 28) and passes it to the fork 27' of the corresponding mechanism contained in the box 3.

The tooth 13 is followed by a similar one 13' which acts upon the return rollers 33 (all arranged in the same plane) causing

the return of those beams that have been 65 displaced by the tooth 13.

The parallelogram system returns to its original position leaving the shuttle 5 upon the fork 27' engaged by the spring teeth 28'.

A continuous exchange of shuttles then 70 takes place between the upper and lower mechanism causing the threads of the shuttles (the end of the threads having been previously fixed to the fabric feeder 16) 75 forcing the warp to cross those from the bobbins 10 (carried by the thread guides 12) forming the weft.

The movable supports 25 may be suitably 80 provided with rods 26 each of which carries a fork 27. In this case the shuttles are lifted in groups, but the lifting of any number of shuttles may be prevented by frictionally connecting each rod with the support and providing it with a stop 26' engaging with control stops as in a Jacquard mechanism.

Figures 5 and 6 show constructional details of the shuttles. Figure 5 shows the 90 box formed of two pieces of sheet metal 35, 35', hinged at 36 and which are clasped together by the lips opposite to the hinge.

The hanks 37, Figure 6, of flat shape, are 95 inserted in the box, the end of the thread 37' unwinds therein passing through the lid 38, Figure 7, upon which is mounted the thread breaking alarm device which also serves to keep the thread in tension.

This arrangement consists of a stirrup 100 39 fixed to the lid 38 in whose slit 39' slides a bridge 40 drawn towards 38 by a spring 41 of slightly lower strength than the breaking load of the thread.

The end 37' of the hank passes through 105 suitable slits provided in the members 38, 40 and 39 and is engaged with the bridge 40 and two springs 40', with sufficient friction to maintain the threads stretched between the feeder 16 and the shuttle, and also 110 extend the spring 41 so that the bridge 40 does not establish contact between the terminals 42 of an electric circuit. Should a warp thread (the end 37' break, the bridge 115 closes the circuit between the wires 42 of a relay (not shown) which in turn closes the circuit of an electromagnetic arrangement (not shown) for stopping the machine. These magnetically operated devices are outside of the loom.

All the shuttles are provided with the arrangement described and a similar arrangement may be applied to the bobbin 10.

If the electric current necessary for the 125 working of the electro-magnets of the safety arrangement is not supplied from a main it may be suitably derived from one or more batteries or accumulators 43 arranged within the machine.

In order to allow the conductors to pass out of the upper portion of the machine slots are formed along the length of the pivot 1, with the view of leaving passages 5 between this and the screw shaft 15, Figure 9.

The arrangement for removing the fabric by means of a wheel driven by the rotating member 9 is suitably connected to such wheel arrangement by the flanged joint 44, 45, Figs. 1 and 8. The flange 45 is of the usual types and carries union pivots 46 engaging the slots 47 on the circumference of the flange 44 and allowing a certain angular play between the parts so that when put in motion the driving arrangement is not put into movement until the rotating member 9 has traversed an arc equal to $\frac{360^\circ}{n}$,

²⁰ *n* being the number of bobbins 10. The driving arrangement may be omitted and a batten of suitable construction employed in its place, Figures 15 and 16, which simultaneously advances and beats up the fabric.

³⁰ In the example illustrated in Figure 15, the batten consists of a series of combs 80 arranged around the cylindrical portion where the fabric is woven and provided with rods 81 (traversing platform 2) which are themselves provided with pusher rods 82 acted upon by a cam 83 that lowers them successively, compressing the spring 84.

³⁵ A regulating screw 85 limits the travel of each comb and in order to avoid stressing of the pusher rods these are connected to a rod 82 by a spring 86 much more powerful than the spring 84.

⁴⁰ In Figure 16 the spring 87 always tends to lower the comb while the cam 83' on account of its sector 83''' maintains it raised, only allowing it to be lowered when it passes over the gap 83'''.

⁴⁵ Referring to Figs. 19 and 20 that show on a larger scale a perspective front view and an elevation of the operating means for the warp carriers. The shuttle supports 27 are divided into four groups, 27¹, 27², 27³ and 27⁴ (Fig. 2) which correspond to the beams 31¹, 31², 31³ and 31⁴ and the rollers 32¹, 32², 32³ and 32⁴ arranged in four superposed rows, while 33¹, 33², 33³ and 33⁴ are the return rollers all of which are arranged in the same plane.

⁵⁰ According to the design of the fabric to be made teeth 13 are arranged in a predetermined order at the ends of the short arms 100¹, 100², 100³ and 100⁴, fast with the supports 11 in the planes of rollers 32¹, 32², 32³ and 32⁴. The teeth 13¹ are fixed to the end of the longer arm 100¹ in the plane of the return rollers 33¹, 33², 33³ and 33⁴.

⁵⁵ In the example shown, in one support 11 of the thread guide 12 the teeth 13 are secured to the arms 100¹ and 100³; in the next

support the teeth 13 will be fixed to the arms 100² and 100⁴, and so on alternatively for the other supports 11.

In Figs. 19 and 20 the tooth 13 fixed to the arm 100³ has lowered the roller 32¹, and the tooth 13 fixed to the arm 100¹ is about to lower the roller 32¹. As support 11 continues its movement in the direction of the arrow, the tooth 13 of the arm 100¹ lowers roller 32¹, and the fixed tooth 13¹ by striking against the roller 33³ returns the roller 32³ to its original position.

Owing to this movement, the support 27 will be lifted, bringing the warp carrier or shuttle to the fork 27¹ of the upper platform 3, while fork 27³ is lowered to the platform 7, releasing the warp carrier in fork 27³ mounted in the opposite platform 3.

⁸⁰ The next support 11 will likewise act on rollers 32² and 32⁴.

⁸⁵ Similar controlling means are provided for the forks 27¹ mounted on the platform 3, the motion of the said forks being alternated with that of the forks 27 on the platform 6.

⁹⁰ By suitably adjusting or changing the teeth 13 or their number along the several supports 11 the shuttles are selectively moved so that a great variety of fancy fabrics may be obtained.

⁹⁵ A continuous exchange of warp carriers then takes place between the upper and lower mechanisms causing the threads of the warp carriers (the end of the threads having been previously fixed to the fabric feeder 16) forming the warp to cross the threads from the bobbins 10 (carried by the thread guides 12, one guide being provided for each weft thread) forming the weft.

¹⁰⁰ Figure 10 and the following figures show a variation relating to the driving mechanism by which the equivalent exchange movements of the shuttles are obtained by different means.

¹⁰⁵ These modifications consist of a circular platform 50 in which are one or several circular housing crowns 51 each of which contains a shuttle 52 held by spring pads 53 and 54, the spring pads 54 being actuated by an annular cam 55 which may also be of segmental shape and whose projections bear on the pads 54 forcing them against the shuttle 52.

¹¹⁰ The platform 50 is surmounted by a hollow platform 56 in which are arranged moving sectors 56' (each of which is provided with a certain number of housings 51' similar to the housings 51 and provided with pads 53') together forming a platform corresponding to the platform 50.

¹¹⁵ Each sector is connected by a rod 57 to a bent lever 58 pivoted to the platform 56 and actuated by a cam 60 fast with a rotating member 119.

This latter, similar in shape and function to the rotating member 9 previously described, carries at each arm 111 a thread guide 12 supplied from a bobbin 10.

5 The arms 111 carry at their end projections 113 and 113¹ for balancing the beam 61 which actuates the annular cam 55 by means of the lever 62.

The working of this loom is as follows:
10 When the rotating member 119 is in movement the cam 60 fast with it acts successively upon the bent levers 58 which causes the sectors 53 to be lowered one after the other into contact with the platform 15 50 after which they return to their original position by the action of the spring 63.

When a sector comes into engagement with the platform the shuttles which are contained in either the sector or the platform 20 pass into the empty housing so that when the sector again rises it leaves the shuttles gripped by the spring pads 54 and carries with them the others retained by the spring pads 53'.

25 It is evident that as the annular cam 55 rotates the pads 54 successively come under compression causing a regular exchange of the shuttles.

Rotation of the cam is produced by the 30 levers 62 keyed to the shaft 63 caused to rotate by means of the arm 61 at its other end.

When a sector 56' is in its lowered position the tooth 113 of the arm 111 encounters a beam 61 and causes it to rock displacing 35 the cam 55 thus releasing the retained shuttles so that the sector rises drawing with it the free shuttles during which the tooth 13 strikes against the beam 61 bringing it back to its original position.

40 An alternative method for securing the shuttles by an electromagnetic arrangement may be used consisting of a series of electromagnets 70, Figure 18, arranged so as to correspond with the housings 51 and in place of the pads 53 and 54. A commutator 71 upon which rub the brushes 72 supplies the said magnets with current in an order determined by the relative position of the brushes and by the shape and arrangement of the contacts thus replacing the action 45 of the cams 55.

What I claim is:

1. An automatic circular loom comprising spaced discs, movable warp thread shuttle supports in each disc arranged in pairs facing each other and arranged in a plurality of circular series, a shuttle for each pair of supports and adjustable means for selectively moving the supports of one disc toward their corresponding supports in the opposite disc and vice versa.

60 2. An automatic circular loom comprising spaced discs, movable warp thread shuttle supports in each disc arranged in pairs facing each other and arranged in a

plurality of circular series, a shuttle for each pair of supports, adjustable means for selectively moving the supports of one disc toward their corresponding supports in the opposite disc and means for holding the 70 shuttle in its support in one disc until its corresponding support in the opposite disc begins its return movement and vice versa.

3. Automatic circular loom comprising in combination, fork-shaped supports for the shuttles of the warp threads arranged in one or more circular series on the opposed faces of discs spaced from one another, a parallelogram system for each support for imparting an alternating motion to the supports, beams for actuating the parallelogram system each provided with an operating roller and a return roller, operating teeth and return teeth mounted in the turning supports of the thread-guides for the weft and co-operating with the rotation of the thread-guides and successively with operating and return rollers, respectively, for lifting and lowering the supports for the above said shuttle, means for withholding the shuttles 80 of the warp threads in the support of one disc, until the corresponding support of the other disc begins its return motion, and means for stopping the loom when a weft or warp thread breaks.

4. Automatic circular loom comprising in combination, movable supports for the shuttles of the warp threads, arranged in one or more circular series on the opposed faces of discs spaced from one another, a parallelogram system for each support for imparting an alternating motion to the supports, beams for actuating the parallelogram systems, each provided with an operating roller and a return roller, the operating rollers being divided into one or more groups arranged in horizontal superposed planes, while the return rollers are arranged on one horizontal plane only, operating teeth and return teeth mounted in the turning supports 100 of the thread-guides for the weft and co-operating with the rotation of the thread-guides and successively with the operating and return rollers respectively, for lifting and lowering the supports of the shuttles for the warp threads, the operating rollers being movable and capable of being fixed in correspondence with one of the planes on which the operating rollers are arranged, for varying the succession of the motion of the shuttles for the warp threads, means for withholding the shuttles for the warp threads in the support of one disc, until the corresponding support of the other disc begins its return motion, and means for stopping the loom when a weft or warp thread breaks.

5. In an automatic circular loom, two circular sets of warp shuttle supports, the supports of one set arranged opposite those of

- the other set, means to operate said supports to transfer warp shuttles from one set to the other comprising means to positively move the supports to transfer their shuttles and
5 means to positively retract the supports, supporting arms rotating with respect to said means and teeth carried by said arms to operate the transfer means, and a tooth on each arm coming into operation after
10 the transfer has been effected to actuate said retracting means.
6. Automatic circular loom comprising in combination fork-shaped movable housings for the warp thread shuttles, arranged in one
15 or more circular series on the opposed faces of fixed discs spaced from one another, means for mechanically displacing in a predetermined succession the housings on one plane towards the corresponding housings on
20 the other and vice versa, shuttles in the form of flat boxes vertically mounted in a radial direction in the housings; lugs on the opposed sides of each shuttle for engaging the fork branches and adapted to co-operate
25 with resilient teeth secured to the discs for retaining the shuttle, when this is released by the fork on its return motion, and means for stopping the loom, when a warp or weft thread breaks.
- 30 7. Automatic circular loom comprising in combination, movable supports for the shuttles of the warp threads arranged in one or more circular series on the opposed faces of fixed platforms spaced from one another; means for mechanically displacing in a predetermined succession the supports of one platform towards the corresponding supports on the other platform and vice versa; means for retaining the shuttles for
35 the warp threads in the supports on one disc, when the corresponding support on the other disc begins its return motion, and means for stopping the loom, when a warp or weft thread breaks, comprising bridges
40 mounted on the shuttles for the warp threads
45 and on the bobbins for the weft threads, respectively, and provided with friction springs between which passes the warp thread and the weft thread, respectively, and which tend to keep the bridge at a distance 50 from two contacts placed in the electric circuit for stopping the loom, against the action of one or more springs tending to establish contact by means of the bridge between the contacts or terminals.
- 55
8. In an automatic circular loom, two circular sets of warp shuttle supports, the supports of one set arranged opposite those of the other set, lazy tong mechanisms to operate the supports, actuating levers for said mechanisms arranged at different levels whereby the sets are separated into a plurality of series, a retracting means on each lever, supporting arms rotating past said levers and retracting means, and one or more 60 teeth in each arm arranged to operate said retracting means after its support has transferred its shuttle.
- 65
9. Automatic circular loom comprising in combination movable supports for the shuttles 70 for the warp threads arranged in one or more circular series of discs spaced from one another facing one another, means for mechanically displacing in a predetermined succession the supports of a disc towards the corresponding supports and vice versa, means for withholding the shuttle of the warp threads in the support of one disc, until the corresponding supports of the other disc begins its return motion, means for stopping 75 the loom when a weft or warp thread breaks, and a fabric feeder formed of a battery consisting of a series of combs actuated by cams against the action of springs, the travel of each comb being connected to the corresponding comb by a spring more powerful 80 than the said former spring.
- 85
- In testimony that I claim the foregoing as my invention, I have signed my name.
- LUIGI BRUNO.
